UNITED STATES PATENT OFFICE.

RICHARD A. OGLESBY, OF SOUTH BEND, INDIANA, ASSIGNOR TO QUICK ACTION IGNITION COMPANY, OF SOUTH BEND, INDIANA, A CORPORATION OF INDIANA.

DETACHABLE MAGNETO-ARMATURE HEADS AND CORE.

1,338,151.

Specification of Letters Patent. Patented Apr. 27, 1920.

Application filed March 19, 1917. Serial No. 155,918.

To all whom it may concern:

Be it known that I, RICHARD A. OGLESBY, citizen of the United States, residing at South Bend, in the county of St. Joseph and 5 State of Indiana, have invented certain new and useful Improvements in Detachable Magneto-Armature Heads and Cores, of which the following is a specification.

My invention relates to improvements in 10 detachable magneto armature heads and core and it appertains more especially to the features pointed out in the annexed claims.

The purpose of my invention is to provide a form of armature construction by which 15 laminated heads and the core connecting the same are made detachable so that marked economies of production are attained by reason of the fact that the coils can be machine wound in advance quantities on sym- 20 metrical spools or holders and subsequently assembled on an interlaced core and its heads thus obviating the tedious and expensive winding operations when the core and heads are made integral.

With these and other ends in view I illustrate in the accompanying drawing such an instance of adaptation as will disclose the fundamental features without limiting myself to the specific details shown.

Figure 1 shows a perspective view of the detachable laminated members.

Fig. 2 is an elevation in section of a coil in position on the core between the armature heads.

Fig. 3 is a transverse elevation in section showing the symmetrical relation of the coil.

Fig. 4 is an elevation of a detached head lamination with an overhanging projection.

Fig. 5 is an elevation of a detached head and combined core lamination.

Fig. 6 is an elevation of a detached head lamination with one edge cut off.

Fig. 7 is an elevation of assembled heads and core, instancing heads without overhanging projections.

In practically carrying out my invention I utilize adaptations of the features instanced in the drawings as will secure results with the least expenditure of time and materials, and which will enable one to use laminated magnet heads, whether used specifically for armatures or otherwise, combined

with interlaced cores so as to permit the very ready assembling of machine wound 55 coils thereby avoiding costly and slow hand-made windings.

When the cores are made with detachable heads a source of weakness lies in the joining faces of the heads and cores which in 60 time become oxidized and cause a serious reduction in the magnetic efficiency of the magnet. Such a construction however permits of the use of machine wound magnets but under a serious handicap. Whenever 65 the heads and cores are formed of one piece stampings the magnets can not be threaded onto the core but they must be dealt with individually each magnet being hand-wound. To avoid this expense and enable one to use 70 machine wound magnets into which core members may be inserted from opposite ends of the magnet I form the core part with an integral head portion at one end only 75 and assemble these in a right and left relation with head portions alone so as to build up the required dimension of complete heads.

As instanced in the drawing the construction which enables these ends to be attained embodies the use of full head stampings 1 80 combined head and core stampings having a head portion 2 and a core 4 and narrow head pieces 3. The parts are assembled substantially as shown in Fig. 1 so as to produce right and left hand members which 85 interlace into each other, the core parts being placed side by side within the inner magnet tube 9. In order that such members may be handled as independent units they are assembled as shown in Fig. 1 and held 90 in position by rivets 5 which pass through all the laminations of each group. When the cores 4 are threaded through the magnet, holes 7 at the ends of the cores 4 will register with holes 6 formed in the head plates 95 1. Screws may be passed through all the holes 6 and 7 and the completed magnet attached to any desired support by means of such screws.

The narrow heads 3 when assembled in 100 alternate relation in the completed heads form slots 10 beneath their lower edges 15 into which the free end of the core parts is placed. The outer tube 8 of the magnet may surround a secondary coil on tube 17 or it 105 may surround a single winding or a primary

coil on the inner tube 9. At any event the windings are retained within the tubes by heads 16.

It is immaterial as to the specific kind of heads which are used. Those having overhanging portions 14 admit of an increased winding space thereunder. If desired heads 12 and core 11 may meet the needs of special exigencies. An outer thickened assembling plate 13 through which counter sink fastening screws can project while passing through holes 6 may be provided if desired.

From the brief description it will be seen that a very simple solution of a rather difficult problem is secured by means of the different parts instanced. I am enabled to secure economies of production, standardization of parts and an efficiency of operation hitherto indifferently attained.

20 I do not limit myself to the specific proportions or shapes of the heads or cores and neither do I limit myself to any special form of magnet but I lay claim broadly to interlaced magnetic material heads and core parts wherein one end of a core part has an enlargement formed integrally therewith which may be expanded transversely of the core axis as desired by adding laminations thereto on either side of the core so as to 30 meet any required dimensional conditions of thickness of heads, etc.

What I claim is,

1. In armature structures laminated core and head members having enlargements with 35 curved outer surfaces at one end, as a group to constitute a half-unit, duplicate laminæ differently assembled forming a separate half-unit, an independently formed magnet coil having an opening therethrough and 40 adapted to receive the core part of each group of laminæ, and means for holding the groups in engagement with each other so that the curvature of one will be concentric

with that of the other, the center of such curves lying entirely without the assembled 45 parts.

2. In electromagnets for armatures, etc., combined core and head laminæ having an enlargement constituting an externally curved projection at one end of the core 50 only, other laminæ similarly curved as head portions only, means for holding the several laminæ assembled to constitute a unit head and half-core; another unit formed with duplicate members but differently grouped, 55 each head having a slot formed therein, both slots being out of alinement with each other but adapted to receive the free ends of the core portion of each unit, a magnet spool threaded over the core parts and means for 60 holding the several parts in assembled relation, so that the curved arcs are approximately at the same radius whose center is entirely outside of the assembled parts.

3. An article of manufacture comprising 65 a combined magnet core and curved head lamination formed integrally with each other, similarly formed duplicate laminæ assembled adjacent each other to constitute a group, independently formed head laminæ 70 similarly curved and assembled adjacent the other heads to constitute a half-core unit, duplicate core and head parts constituting a second group, similarly shaped curved heads assembled with the heads of the second group, to also constitute a half-core unit both units being assembled together so as to form a winding space between and beneath the heads.

In testimony whereof I affix my signature 80 in the presence of two witnesses.

RICHARD A. OGLESBY.
